BOILER

Filed Aug. 25, 1928

UNITED STATES PATENT OFFICE

WILLET E. STARK, OF EAST CLEVELAND, OHIO, ASSIGNOR TO THE BRYANT HEATER & MANUFACTURING COMPANY, OF CLEVELAND, OHIO, A CORPORATION OF OHIO

BOILER

Application filed August 25, 1928. Serial No. 302,017.

This invention relates to boilers or water heaters adapted for use in connection with buildings and the like, and has more particularly to do with improving the appearance 5 of the boiler.

One of the important objects of the present invention is to construct a boiler in such a manner that the burner cocks and manifold will be entirely enclosed within the boiler 10 housing to thereby prevent the burner cocks from being accidentally turned on or off and at the same time to materially improve the appearance of the boiler.

With the objects above indicated and other 15 objects hereinafter explained in view, the invention consists in the construction and combination of elements hereinafter described and claimed.

Referring to the drawings,

20 Figure 1 is a fragmentary vertical sectional view of the lower portion of a boiler embodying the present invention.

Fig. 2 is a front elevational view looking 25 into the boiler with the door removed.

Fig. 3 is a horizontal sectional view showing the manner in which the frame is supported by the boiler base.

In the drawings, 10 represents a cast iron base upon which the water sections 11 are 30 adapted to rest. The water sections 11, four of which are herein illustrated although any desired number may be employed, are adapted to be positioned side by side and are connected together at the rear lower portions 35 thereof by a water manifold 12 and at the upper forward portions thereof by an outlet manifold which is not herein shown. Preferably beneath the sections are burners 13 supported upon a burner support 14 prefer- 40 ably formed integral with the side walls of the base 10. The burners 13 have connected thereto mixer tubes 15 which, in turn, communicate by pipes 16 with the gas manifold 17 connected to any suitable source of supply. The gas from the manifold 17 to the 45 burners 13 is controlled by individual burner cocks 18 disposed between the manifold 17 and the pipes 16.

The products of combustion from the burners 13 pass upwardly between the adjacent

sides of the sections 11 to thereby heat the latter and subsequently pass out through a suitable opening in the top of the boiler to a chimney leading to atmosphere, these latter members not being herein illustrated inasmuch as it forms no part of the present invention and is but the customary construction.

The boiler sections 11 are ordinarily entirely enclosed within a heat insulated housing, the front and rear walls 19 and 20, respectively, being herein shown.

In the ordinary construction of boilers or water heaters of the type referred to, it is customary to have the gas manifold 17 and burner cocks 18 positioned upon the outside of the boiler or housing and, as a result, are unprotected which very often results in accidental turning on or off of the burner cocks by children or other persons. Furthermore, 70 having the manifold 17 and burner cocks 18 on the outside of the boiler, detracts materially from the appearance of the boiler and it is, therefore, the intention of the present invention to overcome these objections.

The water sections 11 are provided with forwardly extending offset portions 21, which project forwardly of the inner front plate 22 of the cast iron base 10 sufficiently to provide a space 23 directly beneath the offset portions 21 for a purpose to be later described. These offset portions 21 of the sections 11 engage a transversely extending heat insulating member 24 which, in turn, is carried by a supporting plate 25 which has its rear edge provided with a rearwardly extending flange 26 supported upon the upper edge of the inner front plate 22. The front wall 19 of the housing is moved outwardly as shown in Fig. 1 adjacent the front edges of the sections 11 instead of extending directly upwardly above the inner front plate 22 as in the customary construction. This front wall 19 is provided with an opening in its lower portion which is adapted to receive therein the cast iron frame 27. This cast iron frame 27 has a rearwardly extending flange 28 along its upper edge upon which the front wall 19 is adapted to rest and disposed between the lower edge of the front

wall 19 and the flange 28 is the forward end of the supporting plate 25.

The frame 27 is provided with a pair of laterally extending ears 29 adjacent its mid-portion to which are bolted or otherwise secured the ears of brackets 30, which brackets have transverse openings to receive and support the manifold 17. The inner free ends of the brackets 30 are provided with upward-
ly extending hooks 31, which are adapted to interengage with vertical slots 32 provided in the inner front plate 22 of the base 10. The lower edges of the free ends of the brackets 30 are provided with transverse notches 33 of sufficient width to rest upon the inner front plate 22 adjacent the slotted openings 32. It will, therefore, be noted that the cast iron frame 27 is held in proper relationship with respect to the housing and directly adjacent 20 the opening 23 by means of the brackets 30.

The cast iron frame 27 is provided with an inwardly extending flange 34 adapted to cooperate with a door 35 which, when in closed position, covers the manifold 17 and burner cocks 18 so that the latter cannot be observed from outside of the boiler. This door 35 is provided on its lower edge with a pair of inwardly extending members 36 adjacent the sides thereof, which are adapted to engage 25 with notches 37 provided in the lower portion of flange 34 of the cast iron frame 27. This construction is such that the door 35 in being moved to open position may pivot about the interengaging members 36 and 37 and, 30 if desired, the door may be removed by disengaging these members without the necessity of removing bolts or like attaching means. The upper portion of the door 35 is provided upon its rear side with a spring catch 39, 35 which cooperates with a rearwardly extending tapered web 40 formed upon the inner upper surface of the cast iron frame 27. A knob 41 is attached to the upper portion of the door to facilitate opening and closing of 40 the same. When the door is moved to open position the spring catch 39 is forced over the tapered web 40 to thereby permit its opening so that the burner cocks 18 may be operated and when the door 35 is moved to closed position, the spring catch 39 cooperates with the 45 tapered web 40 and the resiliency of the spring retains the door 35 in closed position.

It will be noted that I have provided an improved boiler construction in which a space 50 is provided directly beneath the sections 11 and entirely within the housing of the boiler wherein the manifold 17 and burner cocks 18 are disposed, thus preventing accidental turning on or off of the burner cocks and at the 55 same time, materially improving the appearance of the boiler by having these elements enclosed within the housing.

While I have described the preferred embodiment of the invention, it is to be understood that I am not to be limited thereto as

changes and modifications may be made without departing from the spirit of the invention as defined in the appended claims.

Having thus described my invention, what I claim is:

1. In a boiler of the character described, a plurality of sections having a space therebeneath, a base supporting said sections, means beneath said sections dividing said space into two chambers, one of which is a combustion chamber, a burner disposed in said combustion chamber, and gas controlling means disposed within said other chamber. 70

2. In a boiler of the character described, a plurality of sections having an enclosed space therebeneath, means dividing said space into two chambers, one of which is a combustion chamber, a burner disposed in said combustion chamber, a gas supply manifold, and means for controlling the flow of gas from the manifold to the burner, said control means being disposed within said other chamber. 80

3. In a boiler of the character described, a plurality of sections having an enclosed space therebeneath, means beneath said sections dividing said space into two chambers, one of which is a combustion chamber, a burner disposed in said combustion chamber, a gas supply manifold, and means for controlling the flow of gas from the manifold to the burner, 90 said manifold and control means being disposed within said other chamber. 95

4. In a boiler of the character described, a plurality of sections having lower offset portions with a space therebeneath, a housing enclosing said sections, the front wall thereof extending adjacent the offset portions of said sections and provided with an opening therein, a plurality of burners beneath said sections, a gas supply manifold extending within said space beneath said offset portions, means for controlling the flow of gas from the manifold to the burners and disposed within said space, and a door for said opening. 100

5. In a boiler of the character described, a plurality of sections having forwardly extending offset portions at their lower ends with a space therebeneath, a housing enclosing said sections and having a front wall extending adjacent said offset portions, an opening in said front wall, a frame disposed within said opening, a door pivotally connected to said frame and adapted to close said opening, a plurality of burners disposed beneath said sections, a gas supply manifold extending within said space beneath said offset portions, and means for controlling the supply of gas from said manifolds to said burners and disposed within said space. 115

6. In a boiler of the character described, a plurality of sections having forwardly extending offset portions adjacent their lower ends with a space therebeneath, a base for supporting said sections, a housing enclosing 120

said sections and having a front wall extending adjacent said offset portions, an opening in the lower portion of said front wall, a frame disposed within said opening, a door pivotally connected to said frame and in substantially the same plane with the front wall when in closed position, a plurality of burners beneath said sections, a gas supply manifold extending within said space beneath said offset portions, and means for controlling the flow of gas from the manifold to the burners and disposed within said space.

7. In a boiler of the character described, a plurality of sections having forwardly extending offset portions adjacent their lower ends with a space therebeneath, a base for supporting said sections, a housing enclosing said sections and having a front wall extending adjacent the offset portions, an opening in said front wall for access to said space, a door for said opening movably connected to said housing, burners beneath said sections, a gas supply manifold extending within said space beneath said offset portions, and means for controlling the flow of gas from said manifold to said burners and disposed within said space.

8. In a boiler of the character described, a plurality of sections having forwardly extending offset portions with a space therebeneath, a base for supporting said sections, a housing enclosing said sections, an opening in the front wall of said housing, a frame disposed within said opening, means associated with said frame and said base for retaining the former in position, a door for said frame adjacent the front portion of said space, burners beneath said sections, a gas supply manifold extending within said space, and means for controlling the flow of gas from said manifolds to said burners and disposed within said space.

9. In a boiler, a plurality of sections having offset portions adjacent their lower ends, a base supporting said sections and having a front plate adjacent the rear portion of said offset portions, burners beneath said sections, and control means for said burners disposed beneath said offset portions and in front of said front plate.

10. In a boiler of the character described, a plurality of sections having a space therebeneath, a housing surrounding said sections and space, a partition dividing said space into two chambers, one of which is a combustion chamber, a burner disposed in said combustion chamber, and gas controlling means disposed within said other chamber, said housing having means providing access to said gas controlling means, and said partition having means providing access to said burner.

11. In a boiler of the character described, a plurality of sections having a space therebeneath, a partition dividing said space into two chambers, one of which is a combustion cham-

ber, a housing enclosing said sections and space and having an opening in one of the walls thereof adjacent the other chamber, a burner disposed in said combustion chamber, gas controlling means disposed within said other chamber and communicating with said burner, said partition having an opening therein for providing access to said burner, means for normally closing said opening in said partition, and means for normally closing said opening in said housing.

In testimony whereof, I hereunto affix my signature.

WILLET E. STARK.
